UNITED STATES PATENT OFFICE.

WILLIAM H. DAMMOND, OF DETROIT, MICHIGAN.

SAFETY SYSTEM FOR OPERATING RAILROADS.

No. 823,513.

Specification of Letters Patent.

Patented June 19, 1906.

Application filed February 17, 1905. Serial No. 246,037.

To all whom it may concern:

Be it known that I, WILLIAM H. DAMMOND, a citizen of the United States, residing at Detroit, county of Wayne, State of Michigan, have invented a certain new and useful Improvement in Safety Systems for Operating Railroads; and I declare the following to be a full, clear, and exact description of the invention, such as will enable others skilled in the art to which it pertains to make and use the same, reference being had to the accompanying drawings, which form a part of this specification.

My invention relates to systems for controlling the motion of trains; and the objects of my improvement are to produce at any desired point on a car, train, or locomotive distinct results corresponding to the conditions "clear," "caution," and "danger" of the track ahead of said car, locomotive, or train. These and other objects I obtain by the safety system hereinafter described more fully and claimed, and illustrated by the accompanying drawings, in which—

25 Figure 1 shows a practical arrangement of track-circuits; Fig. 2, another practical method of distributing the receiving points or stations on the track than that shown in Fig. 1, and Fig. 3 shows the mechanism of the 30 receiving car, locomotive, or train, together with one set of results that may be produced corresponding to the condition "clear," "danger," and "caution" of the track ahead.

At various points along one of the track-rails are located home receiving points or stations, the distance between two consecutive receiving-stations determining at that place the length of the block. These receiving-stations may preferably consist of portions 40 of the track-rail insulated from the adjacent portions thereof, and the side of the track on which these receiving-points are located is hereinafter designated the "home" side of the track. Besides the home receiving-points, I preferably provide in each block a distant receiving point or station, which I preferably locate on the rail not containing the home receiving-points, and the side of the track on which such distant receiving-points are located is hereinafter designated the "distant" side of the track. These distant receiving-points, like the home receiving-points, may preferably consist of portions of the track-rail

insulated from the adjacent portions thereof. These home and distant receiving-points may 55 be distributed in various methods, two practical combinations being shown in Figs. 1 and 2. In Fig. 1 it will be observed the home receiving-points *a b*, &c., are located near the ends of the respective blocks and that 60 the corresponding distant receiving-points *a' b'*, &c., are located in the same blocks with the corresponding home receiving-points, but a little behind the latter. By this arrangement the danger results are produced 65 when the receiving conveyance arrives near the end of the block immediately preceding the obstructed block, and the caution or distant results are produced on said conveyance when the latter arrives at a predetermined 70 point between the end of the first and the end of the second block preceding the obstructed block. In Fig. 2, however, it will be noted that while, as in Fig. 1, the home receiving-points *aa bb*, &c., are located near 75 the ends of the blocks immediately preceding the obstructed block the distant receiving-points *b' b' c' c'*, &c., unlike the case of Fig. 1, are located at the ends of the second block preceding the obstructed block. In other 80 words, the distant receiving-point for any block and the home receiving-point for the next block ahead are located at the same position along the length of track directly protected. It will be noted that in Figs. 1 and 2 85 the blocks are lettered I, II, III, and IV, the direction of traffic in each case being as indicated by the arrow. In block III it will be noted that key *k* in Fig. 1 and key *k'* in Fig. 2 appear, which are omitted from the 90 wiring of the other blocks. These keys are not necessary to the purely automatic block safety operation of the system. Their utility will appear below.

In block III, Fig. 1, is located a track-battery *z*, from which a circuit extends from one pole to conductor 20^a, to key *k*, to conductor 20, to track-rail CC, to bonding-wire *y*, to track-rail C, to conductor 42, to coil of track-relay *r*, to conductor 43, to track-rail H, to conductor *y'*, to track-rail K, to conductor 22, back to battery *z*. Track-relay *r* being energized, as just shown, closes partial circuits from batteries *z* and *z'* to the receiving-points in the preceding block. 100 One of these partial circuits is from one pole

of z^5 to conductor 36, to insulated relay-contact r^7 , to conductor 37, to receiving-point a and from the other pole of z^5 to conductor 38, to track-rail H, and thence through 5 track-rails H K, &c., and bonding-wires y y', &c., to any point, exclusive of distant receiving-points, on the track-rail on the distant side of the track. The other partial circuit here is from battery z^6 , to conductor 10 39, to insulated relay-contact r^8 , to conductor 40, to distant receiving-point a' , and from the other pole of battery z^6 to conductor 41, to track-rail B.

On each conveyance on which the desired 15 results are to be produced I provide a home contact L, which may be an insulated wheel or the like, and a distant contact M of similar construction. These contacts may be selected from the regular wheels of the conveyance, properly insulated, or may consist of extra wheels, as may be desired. In any case, however, they must be insulated from each other and from the remaining portions of the vehicle, the distant contact 20 or wheel being so arranged as to travel on the rail on the distant side of the track and the home contact on the rail on the home side of the track. Suitable contacts l and m are provided by which current may pass 25 from each of these insulated wheels to conductors on the locomotive or car. The operating instrument, located at any convenient point on the conveyance and shown in Fig. 3, is divisible into a home and a distant section. 30 The distant section of the instrument contains a main armature N and an auxiliary armature N', adapted to make certain contacts, as shown below, and controlled as to position by certain electromagnets, as hereinafter described. In the home section of 35 the operating instrument is the main home armature O and the auxiliary armature O', arranged to make certain contacts and to be controlled in position by certain electromagnets, as hereinafter shown. It will be noted that on one end of the main distant armature N is a contact n, which is insulated from said armature N. This contact may consist of any suitable kind of conduct- 40 ing material and is designed to coöperate with two pieces of conducting material, which are insulated from each other and which constitute the circuit-breaker n^2 . Thus if the armature N is rotated to the 45 dotted position and the circuit supplied by the wires 1 and 2 is complete, except for the open circuit between the halves of the circuit-breaker n^2 , then this circuit will again become closed when armature N is suitably 50 rotated, so that the contact n touches simultaneously the halves of the circuit-breaker n^2 , as shown in the full position of the armature N. At one end of the main home armature O and at each end of the auxiliary 55 armatures N' and O' are contacts similar to

the ones just described for the main distant armature, and these contacts shown for the other armatures operate in conjunction with their respective circuit-breakers in manner similar to that just described for the main 70 distant armature.

In addition to the contacts just explained it will be observed the main distant armature N carries two other contacts n^4 and n^5 , which alternately close circuits containing the circuit-breakers n^6 and n^7 . These contacts are insulated from the armature N. The main home armature O carries a contact n^8 , similar in construction and insulated similarly as just shown for the contact-pieces n^4 and n^5 for the main distant armature. This contact n^8 on the main home armature alternately opens and closes the circuit through the circuit-breaker n^9 , according to the position of the rotating armature O.

A retaining-electromagnet P is provided for the main distant armature N, which is supplied from a battery P^2 . When the armature N is once rotated to the dotted position, a circuit through this retaining-magnet is established by way of contact p and the armature N. Hence if the circuit from battery P^2 and around magnet P is opened at any other point than between contact p and the armature N and said armature under the effect of gravity or of springs, for instance, drops to the full position, then even when the former open circuit is closed there remains the open circuit between contact p and armature N, and the retaining-magnet P will therefore remain deenergized, and hence unable to return the armature N to the dotted position. As will appear later, this return is effected at the proper time by the co-operation of the magnets Q and S or the co-operation of magnets V', V, and Q.

In case there is not sufficient and proper difference of mechanical moments between the halves of the respective armatures to cause them under the effect of gravity to return with requisite promptness to their full positions the proper ends may be suitably weighted or springs may be supplied for this purpose.

It is evident that when the keys k and k' in block III, Figs. 1 and 2, are closed the electrical circuits in this block are essentially the same in each case as the showing for the other blocks. In other words, the effect of opening and closing key k, Fig. 1, or key k', Fig. 2, is the same for block II as will be produced in block III by opening and closing relays r', Fig. 1, or r'r', Fig. 2.

One way of promoting the safety of trains 125 against collisions is to cause visible signals to be displayed to the engineman corresponding to the conditions "clear," "danger," and "caution" on the track ahead. In my safety system this result may be produced by pro- 13

viding a signal containing three indicators, one, D, meaning "caution," another, W, meaning "clear," and another, R, meaning "danger" or "stop." These three indicators may be arranged behind a screen which covers the front of the indicator mechanism in such manner that normally the red or danger signal is displayed through an opening in the screen. Clear and caution indicators W and D may be supported normally away from the opening in the screen on hangers provided with armatures adapted to be controlled by magnets. A battery on the locomotive may be grounded on one side; while the other side is connected to one half of circuit-breaker n^9 . From the free half of this circuit-breaker a wire may be run to one half of each circuit-breaker n^6 and n^7 and wires run from the free halves of these circuit-breakers to the magnets controlling the clear and caution indications, the latter magnets being joined by a common conductor to a grounded portion of the locomotive or car. In this way when armatures O and N are both in the dotted positions current from battery A supplies a circuit to conductor 35 through circuit-breaker n^9 by contact n^8 , to conductor 34, through one half of circuit-breaker n^7 , to conductor 53, through circuit-breaker n^6 by contact n^4 , to conductor 21, to magnet x, attracting clear indication W to cover R and be thus displayed, then to grounded wire 52, the other half of this circuit being from battery A to grounded wire 50. If armature O were to remain in the dotted position and armature N dropped to the full position while battery A would remain grounded on one side through conductor 50, yet the circuit on the other side of this battery would now be from A to conductor 35, through circuit-breaker n^9 , by contact n^8 , then to conductor 34, through n^7 by contact n^5 , to conductor 51, around magnet x', causing said magnet to attract D, obscuring R and displaying D, then to common conductor 52 to a grounded portion of the locomotive or car. If armature O now be in full position, then battery A is open-circuited at the circuit-breaker n^9 , and hence no matter what the position of N current is cut off from both magnet x, controlling indicator W, and magnet x', controlling D, and hence the danger-signal R remains displayed. When armature O remains in the dotted position, it will generally be desired in practice that the change from the display of W to the display of D and oppositely shall be effected directly—that is, without R intervening. This may be effected by so arranging circuit-breakers n^6 and n^7 , together with their respective contacts, that in its rotation between full and dotted positions armature N will always make the new contact before breaking the old one.

To show the operation of my system, let it be assumed that a locomotive properly

equipped is in block II, Fig. 1, at a point behind distant receiving-point a'—that is, suppose that this distant point is between the locomotive and the home receiving-point a and that the clear results are being produced on the locomotive; also, let the block III be clear. Now when once the main distant armature N is sent to the dotted position and the auxiliary armature N' is down in its normal (full) position the main armature is maintained in said clear (or dotted) position by magnet P, which is supplied from battery P², the circuit being from battery P² to conductor 3, to electromagnet P, to conductor 4, to contact 5, to contact 6, to armature N', to conductor 7, to conductor 8, to brush m, to insulated wheel M, to track-rail G, to uninsulated locomotive-wheel M', to conductor 13, to conductor 10, to armature N, to contact p, to conductor 11, back to battery P². Again, once the main home armature O is rotated to the clear (or dotted) position it is maintained in that position by the home retaining-magnet P', which is energized by current from retaining-battery P³, the circuit here being from battery P³ to conductor 12, to contact p', to retaining-armature O, to conductor 13, to uninsulated locomotive-wheel L', to track-rail B, to home contact L, to brush l, to conductor 14, to conductor 15, to armature O', to contact 16, to contact 17, to conductor 18, to electromagnet P', to conductor 19, back to battery P³. When the locomotive advances to such position as to cause contact M to be in the insulated section a', the circuit around retaining-magnet P is changed between contact-wheel M and wheel M', the circuit being now from battery P² to conductor 3, to electromagnet P, to conductor 4, to contact 5, to contact 6, to armature N', to conductor 7, to conductor 8, to brush m, to wheel M, to receiving-point a', to conductor 40, to insulated relay-contact z^8 , to conductor 39, through relay-controlled battery z^6 to conductor 41, to track-rail B, to wheel M', to conductor 13, to conductor 10, to armature N, to contact p, to conductor 11, back to battery P². This position of the locomotive causes the relay-controlled battery z^6 and the retaining-battery P² to supply the same circuit, and in order that armature N shall not drop to the full position, giving a false caution result, two alternatives may be chosen from: either the relay-controlled battery z^6 and the retaining-battery P² may be connected, so that opposite poles are grounded, thus causing relay-controlled battery to be thrown in series with the retaining-battery P² in the position of locomotive now considered, or relay-battery may be made sufficiently weaker than retaining-battery so as to cause the resultant electromotive force of the two when connected in opposition to be sufficient to magnetize retaining-magnet P with such force as to cause P to continue holding arm- 130

ture N in the dotted position. As the train proceeds so that the contact M leaves the insulated section a' , then the instant said wheel M is in contact with both receiving-point a' 5 and the track-rail H current from relay-controlled battery z^6 is shunted by wheel M from a' to track-rail H by uninsulated wheels and axles to track-rail B, to conductor 41, back to battery z^6 , and the circuit from retaining-battery P^2 to magnet P is reestablished by the above-described partial circuit to m , to M, and thence through track-rail H to conductor y , to track-rail G, to any uninsulated wheel of the locomotive, to conductor 13, and 10 thence by partial circuit above described through conductor 10, armature N, conductor 11, &c., back to retaining-battery P^2 . When the locomotive proceeds so that wheel M leaves distant receiving-station a' , then 15 the circuit from battery P^2 to retaining-magnet P will continue completed through track-rails and bonding-wires on the distant side of the track, as above explained. In this way magnet P continues energized, and in consequence 20 circuit to signal-magnet x will remain closed so long as the locomotive remains in block II in advance of the home receiving-point a . When the locomotive advances to such a position that L enters the home receiving-point a , then the relay-controlled battery z^5 25 is thrown into the same circuit with the retaining-battery P^3 , the two batteries being either so connected as to be in series or so related to each other and to the magnet P' as to 30 electromotive force and magnetomotive force that the resultant effect of said batteries is to cause P' to continue holding main home armature O in the dotted position, the circuit here being from battery P^3 to conductor 19, 35 to magnet P', to conductor 18, to contact 17, to contact 16, to armature O', to conductor 15, to conductor 14, to brush l , to wheel L, to receiving-point a , to conductor 37, to insulated armature-contact r^7 , to conductor 36, 40 to relay-controlled battery z^5 , to conductor 38, to track-rail H, to wheel L', to conductor 13, to armature O, to contact p' , to conductor 12, back to battery P^3 . When the locomotive continues its trip until L touches BB, 45 then current from P^3 passes to conductor 19, through retaining-magnet P', to conductor 18, to contact 17, to contact 16, to armature O', to conductor 15, to conductor 14, to brush l , to wheel L, to track-rail BB, to conductor y^4 , to track-rail B, to wheel L', to conductor 13, to armature O, to contact p' , to conductor 12, back to retaining-battery P^3 . By the process just described the locomotive 50 will enter block III with the clear results 55 thereon continuing, and the cycle above detailed will recommence.

To explain the behavior of the system under another practical condition, suppose, as before, that the clear results are effected and 60 the position of the locomotive such as to

cause the distant contact M to be on the rail G, the home contact L being on the opposite rail B; but suppose, differently from the previous case, that block III contains a car or engine constituting an obstruction in block 70 III. In this case current from track-battery z^3 is shunted away from coil of track-relay r by the obstructing wheels and axles, the circuit being from battery z^3 to conductor 20^a, to key k , to conductor 20, to track-rail CC, to 75 conductor y^5 , to track-rail C, through obstructing wheel and axle to track-rail H, to conductor y' , to track-rail K, to conductor 22, back to battery z^3 . As armature of track-relay r is now in its open position, the circuit 80 controlled by relay-battery z^6 will be opened at said relay. Hence when the locomotive moves to such a position as to cause distant contact M to enter the distant receiving-point a' the circuit from distant retaining-battery P^2 through retaining-magnet P will be broken between M and M', as the former is separated from the latter wheel by the insulation by which a' is separated from adjacent rails G and H. Hence retaining-magnet P being de- 85 energized main distant armature N will now drop from the dotted position to the full position. The circuit to the apparatus for producing the clear results being now opened at circuit-breaker n^6 and that for producing the 90 distant or caution results being closed by n^5 , connecting the halves of circuit-breaker n^7 , the clear results will now cease and the distant or caution results will be effected. Thus, again using the aforementioned signals as an 95 illustration, circuit to magnet x will be opened at circuit-breaker n^6 and circuit to magnet x' will be closed through circuit-breaker n^7 by contact n^6 . Hence clear signal W will be obscured and caution-signal D will 100 show through the opening in the screen at the same time, obscuring danger-signal R. If the obstruction remains in block III after the distant contact M has left the distant-point a' and until the locomotive proceeds so 105 far as to cause the home contact L to enter the home receiving-point a , then the circuit from battery P^3 to home retaining-magnet P' will be broken at L, since contacts of relay r being open current cannot now pass from 110 home receiving-point a . Thus the circuit through the apparatus capable of producing the clear or caution result will be open at the circuit-breaker n^6 and would remain so were the locomotive to proceed until a distant signal 115 having clear track immediately ahead were reached. Now in obedience to the danger results if they did not include such as to stop the locomotive automatically the 120 engineman would stop the locomotive with the home contact in the home receiving-point a . When the obstructing train, car, or engine leaves block III, so that it becomes 125 safe for the locomotive in block II to proceed, then current from z^3 being no longer 130

- shunted by the obstruction that was in block III will flow from battery z^3 to conductor 20 ^{a} , to key k , to conductor 20, to track-rail CC, to conductor y^5 , to track-rail C, to conductor 42, to coil of relay r , to conductor 43, to track-rail H, to conductor y' , to track-rail K, to conductor 22, back to track-battery z^3 . This current will energize coil of relay r , causing said relay to close a circuit from relay-controlled battery z^5 , this circuit being from relay-controlled battery z^5 to conductor 36, to insulated armature-contact r^7 , to conductor 37, to home point a , to home contact L, to brush l , to conductor 14, to conductor 27, to conductor 28, to returning-magnet V, to conductor 29, to conductor 44, through circuit-breaker p^3 by contact p^2 , to conductor 45, to conductor 13, to wheel L', to track-rail H, to conductor 38, back to relay-battery z^5 . At the same time the multiple circuit branching from that just given between conductor 27 and conductor 29 will be energized, the circuit being from conductor 27 to conductor 46, to returning-magnet V', to conductor 47, back to main circuit at conductor 29. As magnets V and V' are now energized armatures O' and N' will be attracted to the dotted positions, causing contacts t and t' to close circuits through circuit-breakers T and T', and causing circuit-breaker w to close a partial circuit through the circuit-breaker w' . Battery U will now energize returning-magnet Q, the circuit being from battery U to conductor 24, through circuit-breaker T by contact t , to conductor 25, to magnet Q, to conductor 26, back to battery U. At the same time battery Q^2 energizes returning-magnet Q', the circuit being from battery Q^2 to conductor 31, through circuit-breaker T' by contact t' , to conductor 32, through magnet Q', to conductor 33, back to battery Q^2 . This will cause armatures N and O to be attracted by magnets Q and Q' to the dotted positions; but the parts are so arranged that in its descent contact w will close circuit through circuit-breaker w' before contact p^2 in its descent opens the circuit between conductors 44 and 45 at circuit-breaker p^3 —that is, circuits just detailed to magnets V and V' are completed from conductor 44 by way of circuit-breaker w' before the partial circuits to said V and V' are opened at circuit-breaker p^3 , the new partial circuit being from conductor 44, through circuit-breaker w' by contact w , to conductor 30, back to the previous route by conductor 13. Armatures N and O being now in the clear or dotted position the clear results will be effected, as shown before, and the locomotive will proceed to block III. When the home contact leaves the receiving-point a and enters track-rail BB, current from relay-controlled battery z^5 to magnets V and V' will be cut off at the insulation, separating receiving-point a from the adjacent track-rail sections. Hence magnets V and

V' being deenergized armatures N' and O' will drop to their normal or full positions; but the parts are so arranged that contact 16 will touch contact 17 before t' opens the circuit through circuit-breaker T'. In other words, the circuits above described from battery P^2 to magnet P and from battery P^3 through magnet P' by way of contacts p and p' will be reestablished between M and M' on one side and L and L' on the other side, and as wheels M and M' are now connected by track-rail BB the circuits from batteries P^2 and P^3 will now be completed through magnets P and P' and the cycle above detailed as beginning in block II will now recommence in block III. 80

As it frequently occurs in practice that trains should stop even when there is no obstruction on the block immediately ahead—for instance, when the track becomes insecure, but does not interfere with the circuits for the foregoing automatic operation of my system—the keys k , Fig. 1, and k' , Fig. 2, are provided, by which circuit from relay-controlled batteries may be opened. Thus when an operator desires to stop a train ahead of which there is no obstruction he has but to open key k or k' , thus cutting off current from receiving-points behind and the proper caution and danger results will be effected on a following train, car, or engine as the latter enters the signal-points affected, as shown above. It may sometimes be desired to return from a caution to clear results while the receiving-locomotive is on a distant receiving-point, and for this purpose I provide the partial circuit from M to brush m , to conductor 8, to conductor 23, through magnet S, to conductor 1, through circuit-breaker n^2 by contact n , to conductor 2, to conductor 10, to conductor 13, to wheels M' and L'. It will be evident that this partial circuit may affect through distant receiving-points, track-rails, and bonding-wires y y' , &c., control of returning-magnet S by circuits from relay-controlled batteries z^6 z^7 z^8 z^9 , &c., in manner similar to the control of magnets V and V' by circuits, as above shown, from battery z^5 , by way of home receiving-point a . When circuit from relay-battery through S is opened at circuit-breaker n^2 , then, similarly as shown for circuit-breakers w' and p^3 , an alternative completing partial circuit is offered from conductor 1, through one-half of circuit-breaker n^2 , to conductor 48, through circuit-breaker n^3 by contact n' , to conductor 49, and back to the circuit through magnet S and by way of circuit-breaker n^2 , conductor 2, &c. The contacts 5 and 6, circuit-breakers n^2 , T, and n^3 are arranged in the same relative positions as the showing above detailed for contacts 16 and 17, circuit-breakers T', w' , and p^3 . 115

Referring to Fig. 3, armature O may be used for the purpose of so controlling two valves that when O is up in the dotted position one of these valves is open and the other 130

closed, and when O is down in the full position the former valve is closed and the latter open. The last-named valve may be used to effect the emergency application of the air-brakes, while the other valve is inserted in piping leading from the boiler to the cylinders of a locomotive. Armature N may be employed for similarly operating two valves, one being inserted in the same steam-piping 5 with the steam-valve controlled by O and only partly closed when N is down in the full position, while the other valve is used for effecting a relatively light application of the air-brakes. Then when both N and O are 10 up in the dotted position both steam-valves are fully open and both air-valves are closed. Hence the train will be permitted to run at full speed. If N is down in the full position and O up in the dotted position, steam is 15 partly shut off (by the valve controlled by N) and a light application of the air-brakes made, so that the train is automatically slowed down. If O is down in the full position, then no matter what the position of N 20 steam is shut off (by the steam-valve controlled by O) and an emergency application of the air-brakes made.

It was set forth at the beginning of this specification that one of my objects was to 25 produce definite results on the locomotive, car, or train corresponding to the condition of portions of the track ahead. It was also explained above that among such results my invention includes control of signaling apparatus. In the valve operation just detailed 30 is illustrated how automatic operation of speed-controlling mechanism is also included in the results producible by my system. Evidently in effecting speed control in the way 35 just indicated my magnets P and P' and armatures N and O instead of acting as signal-controlling means act as speed-controlling means.

Having thus described my invention, what 40 I claim is—

1. A vehicle adapted to travel on electrically-conducting track-rails, suitable track-circuits, electromechanical means carried by 45 said vehicle and in circuit with an electric source on the vehicle, the circuit to said electromechanical means being operated by the track-circuits and capable of operating means by which to signal three distinct instructions for a block, switching means on 50 said vehicle and controlling the circuit to said electromechanical means in such manner that when said switching means is in a predetermined position said electromechanical means is prevented from permitting a 55 certain one of said instructions to be signaled.

2. A vehicle adapted to travel on electrically-conducting track-rails, suitable track-circuits, electromechanical means carried by 60 said vehicle and in circuit with an electrical

source on the vehicle, the circuit to said electromechanical means being operated by the track-circuits and capable of operating means for signaling in any block to stop, to slow down, or to run at full speed, according 70 to conditions obtaining at predetermined places, switching means on said vehicle and controlling the circuit to said electromechanical means in such manner that when said switching means is in a certain position said electromechanical means is thereby prevented from permitting said signaling means to indicate to run at full speed. 75

3. In a safety system for railroads, a track containing insulated sections, a vehicle thereon provided with insulated contacting means adapted to make electrical contact with a track-rail, a partial electric circuit on the vehicle including an electric source thereon and containing a portion of track-rail and an un-insulated portion of the vehicle, said insulated contacting means causing said partial circuit alternately to become closed through a portion of track-rail and to be thrown in circuit with a partial circuit extraneous to 85 the vehicle, electromagnetic means on the vehicle for producing a definite result thereon and adapted to operate independently of the direction in which current is supplied thereto, said electromagnetic means being 90 controlled by the partial circuit on the vehicle when said partial circuit is closed through said track-rail portion, or is thrown in circuit with the partial circuit extraneous to 95 the vehicle, substantially as described. 100

4. A track containing insulated sections of rail, a vehicle thereon supplied with insulated contacting means, a partial electric circuit on the vehicle supplied from an electric source thereon, electromagnetic means on 105 the vehicle controlling electromagnetic devices for producing definite results thereon and in turn controlled by the partial circuit being closed, a partial circuit from a source of electricity extraneous to the vehicle and including contacting means on the track insulated from adjacent portions of track-rail, said insulated contacting means of the vehicle and uninsulated portions of said vehicle being adapted to complete said partial circuit from said extraneous source through 110 electromechanical means on the vehicle for closing the circuit controlling said electromagnetic means. 115

5. In a safety system for railroads, a track containing insulated sections, a locomotive or car thereon carrying insulated contacts adapted to travel on the track-rails, electromagnetic means for producing on the locomotive or car definite and distinct results corresponding to the conditions clear, caution and danger of predetermined portions of the railroad in such manner that the danger result will be produced when current controlled by said electromagnetic means 120 125 130

ceases, circuits from an electric source on the locomotive or car and including the insulated contacts controlling the current to the electromagnetic means for producing the clear, danger and caution results thereon, and electrical means on the track and extending between insulated sections of the track-rails determining which results shall at definite times be produced on the locomotive or car.

6. A track divided into blocks of lengths determined by insulating means between sections of track-rail, contacting means in a block and insulated from adjacent portions of track-rail, a source of electricity electrically connected to track-rails on opposite sides of the track in a block, means adapted to be supplied with current from said source and controlling a partial circuit from an electrical source to said insulated contacting means and to a track-rail in such manner that said partial circuit shall be broken when said controlling means is deenergized, the circuit-controlling means so communicating with said electrical source connected to said opposite track-rails that current from said source shall be shunted away from the controlling means when an electrical conductor connects rails on opposite sides of the track in the block to rails of which said electrical source is connected, a vehicle on the track provided with insulated contacting means adapted to travel on a track-rail, means on the vehicle for producing definite results thereon and electrically connected to uninsulated portions of the vehicle and to the insulated contacting means thereof, said means for producing the results being adapted to produce a certain result when the vehicle-contacting means touches an insulated track-contacting means the said controlled partial circuit to which is unbroken and to produce a different result when the insulated contacting means of the vehicle touches an insulated track-contacting means the said controlled partial circuit to which is broken, substantially as described.

7. In a safety system for railroads, a locomotive or car, a source of electricity thereon, a switching device for causing the electric source alternately to supply current to either or both of two circuits for producing certain results on the locomotive or car and to open said electric circuits, electromagnetic means on the locomotive or car supplied from an electrical source thereon for controlling said switching device, electromagnetic means on said locomotive or car for diverting the current from an electrical source thereon to one or both of the circuits for producing said results, insulated contacts on the locomotive or car and in the circuits controlling said switching and diverting devices by which said circuits may be completed through rails of the track and uninsulated portions of the locomotive or car.

8. In a safety system for railroads, a diverting device on a locomotive or car by which current from an electrical source thereon may be supplied to either or both of two devices for producing results corresponding to the conditions clear and caution ahead, electromagnetic means for controlling said diverting device in such a manner that when said controlling means is energized it will cause the diverting device to send current to the devices for producing the results corresponding to clear ahead and when said controlling means is deenergized it will cause the diverting means to send current to the devices for producing the results corresponding to caution ahead, a switching device in the circuit to said means for controlling the diverting device such that when circuit to said controlling means is once opened at any other point said switching device will itself open and thus prevent subsequent closing of said circuit at said other point from again completing the circuit to said controlling means, electromagnetic means on said locomotive or car adapted to receive current from an electrical source extraneous to said locomotive or car which when energized will close a circuit through said device for controlling said diverting device when the circuit by way of said switching device is open at any other point and will cause said controlling device to remain closed until said other open circuit shall have become closed.

9. A source of electricity on a locomotive or car, electrically-controlled means on said vehicle for producing predetermined results thereon corresponding to conditions obtaining at a predetermined portion of a railroad, a switching device for operating a circuit from said electrical source, said circuit being adapted to actuate said electrically-controlled means and said switching device in turn so influenced by said electrically-controlled means that in case the circuit from said electrical source to said controlled means is opened at any other point than at said switching device said device will itself become open and thereby prevent the said circuit from becoming complete on the closing of the open circuit at said other point.

10. A source of electricity on a locomotive or car, electrically-controlled means on said vehicle for producing predetermined results thereon corresponding to conditions obtaining at a predetermined portion of a railroad, a switching device for operating a circuit from said electrical source, said circuit being adapted to actuate said electrically-controlled means and said switching device in turn so influenced by said electrically-controlled means that in case the circuit from said electrical source to said controlled

means is opened at any other point than at said switching device, said device will itself become open and thereby prevent the said circuit from becoming complete on the closing of the open circuit at said other point, electromagnetic means adapted to cause said switching device to close at the proper time and to remain closed until the open cir-

cuit at said other point has become closed through a predetermined partial circuit.

In testimony whereof I sign this specification in the presence of two witnesses.

WILLIAM H. DAMMOND.
